REEL

Arthur A. Bureau, Chicago, and Edson M. Denny, Oak Park, Ill., assignors to Western Electric Company, Incorporated, New York, N. Y., a corporation of New York

Application October 30, 1946, Serial No. 706,632

6 Claims. (Cl. 242—123)

1

This invention relates to reels and more particularly to light weight metal reels having annularly shaped hollow heads.

An object of this invention is to provide a light weight reel of simple and inexpensive construction having a high degree of strength and durability commensurate with its weight.

In accordance with one embodiment of the invention, a reel is provided having a cylindrical drum to which is welded, at each end thereof, an annularly shaped hollow head comprising an inner annular member having an outer peripheral flange rounded outwardly to abut an inwardly extending inner peripheral flange of an outer dish-shaped annular member having an inner annular flange rounded inwardly to a point substantially in line with the abutting outer peripheral flanges of the two members and then extended straight to abut the inner annular edge of the first member, which is disposed at right angles thereto, the two members being continuously welded together at their outer and inner lines of juncture and similarly welded to the periphery of the drum at two spaced lines of welding, one of the latter lines of welding being substantially in line with the outer peripheral line of welding of the abutting flanges of the two members.

Other objects and features of the invention will become apparent from the following detailed description taken in conjunction with the accompanying drawing, in which:

Fig. 1 is a side elevational view, partly in section, of a reel embodying the features of the invention;

Fig. 2 is an enlarged fragmentary cross-sectional view taken on the line 2—2 of Fig. 3; and

Fig. 3 is a fragmentary end elevational view of the reel.

Referring to the drawing, it will be observed that a reel embodying the features of the present invention comprises a pair of heads 10—10 secured to opposite ends of a straight cylindrical drum 11 having, in the present embodiment, open ends, the drum being formed from a sheet of metal cut to the proper size and rolled into a cylinder with its edges abutting and welded together, as indicated at 12. The reel is of all metal construction and may be used to support cable or other strand material which is wound upon the drum 11.

Each of the reel heads 10 comprises annularly shaped inner and outer sheet metal members 13 and 14, respectively, the members being so shaped and cooperating when assembled and fixed to

2

each other to form a hollow head, as clearly shown in Fig. 2. The inner member 13 has its outer peripheral portion bent outwardly and rounded to form a flange 17 which extends from a main flat portion 18. Spaced from and parallel to the main flat portion 18 of the member 13 is a main flat portion 19 of the outer member 14, which has its outer peripheral portion bent inwardly and rounded to form a flange 20 which, at its edge, meets the corresponding edge of the flange 17 of the inner member 13. The flanges 17 and 20 of the members 13 and 14, respectively, have their opposed edges abutting and thus cooperate to form an annular rim having a rounded or semi-circular cross-section at its periphery, the members being welded together where their annular flange edges abut to form a continuous weld 21.

At its inner peripheral portion, the outer member 14 is bent inwardly and rounded to form a flange 22 which extends from its main flat portion 19 to a point 24 substantially in line with the welded annular flange edges of the members 13 and 14. From this point 24, the flange 22 extends straight or parallel to the axis of the drum 11 and in abutting relationship with the peripheral surface of the drum and also with the inner peripheral edge surface of the inner member 13 with its annular end edge terminating in the plane of the inner surface of the main flat portion 18 of the member 13. The point 24 of the flange 22, in addition to being in alignment with the welded flange edges, is substantially in alignment with the annular end edge of the drum 11. At the juncture of the flange 22 of the member 14, with the inner peripheral edge surface of the inner member 13, the head members 13 and 14 are welded together and also to the peripheral surface of the drum 11 to form a continuous weld 25. Each head 10 is also welded to the outer peripheral edge of the drum 11 to form a continuous weld 26.

From the above description of the outer head member 14, it will be apparent that it is of an annular dish-shaped formation with its inner flange 22 of greater depth than its outer flange 20, whereby it may abut and be continuously welded at 25 to the inner annular edge of the main flat portion 18 of the inner head member 13 and to the drum 11. This arrangement, taken with the continuous weld 21 provided at the annular abutting outer peripheral edges of the flanges 17 and 20 of the two head members, results in a reel provided with hollow light-weight heads having a high degree of strength commensurate with

their weight. Also, with the continuous welds 25 and 26 of the heads 13 and 14 to the drum 11, a very rigid joining of the heads to the drum is provided.

What is claimed is:

1. A reel comprising a drum and an annular hollow head on said drum, said head comprising solely a pair of inner and outer annular metal members arranged in spaced relation one to the other to provide a single unobstructed space in the head and having outer peripheral flanges directed toward and abutting each other at their edges, said members having plane surfaces for the greater portions of the areas, said outer member having an inner peripheral flange engaging the 15 periphery of and being secured to said drum and abutting the inner peripheral edge of the inner member, the members being bonded together at their abutting lines of juncture.

2. A reel comprising a drum and an annular hollow head on said drum, said head comprising solely a pair of inner and outer annular metal members arranged in spaced parallel relation one to the other to provide a single unobstructed space in the head and having similarly rounded outer peripheral flanges directed toward and abutting each other at their edges to form a rim of semi-circular cross section, said outer member having a rounded inner peripheral flange terminating in a straight portion in engaging relation with the periphery of and being secured to said drum and abutting the inner peripheral edge of the inner member, the members being bonded together at their abutting lines of juncture.

3. A reel comprising a cylindrical drum having open ends and an annular hollow head on said drum, said head comprising solely a pair of inner and outer annular metal members arranged in spaced relation one to the other to provide a single unobstructed space in the head and having outer peripheral flanges directed toward and abutting each other at their edges, said members having plane surfaces for the greater portions of their areas, said outer member having a rounded inner peripheral flange terminating in a straight portion in engaging relation with the periphery of the drum beginning at an annular end edge surface of and being secured to said drum and extending inwardly from said drum edge surface to abut the inner peripheral edge of the inner member, the members being bonded together at their abutting lines of juncture.

4. A reel comprising a cylindrical metal drum having open ends and an annular hollow head on said drum, said head comprising solely a pair of inner and outer annular metal members arranged in spaced relation one to the other to provide a single unobstructed space in the head and having outer peripheral flanges directed toward and

abutting each other at their edges, said outer member having a rounded inner peripheral flange terminating in a straight portion in engaging relation with the periphery of the drum beginning at an annular end edge surface of said drum and extending inwardly from said drum edge surface to abut the inner peripheral edge of the inner member, the members being bonded together at their abutting lines of juncture and to the periphery of said drum at the juncture of said straight portion of the outer member with the inner peripheral edge of the inner member and the outer member to the periphery of said drum at its annular end edge surface.

5. A reel comprising a cylindrical metal drum having open ends and annular hollow heads at opposite ends of said drum, each of said heads comprising solely a pair of inner and outer annular metal members arranged in spaced parallel relation one to the other to provide a single unobstructed space in the head and having similarly rounded outer peripheral flanges directed toward and abutting each other at their edges to form a rim of semi-circular cross section, said members having plane surfaces for the greater portions of their areas, said outer member having an inner peripheral flange engaging the periphery of the drum beginning at an annular end edge of said drum and extending inwardly from said drum edge to abut the inner peripheral edge of the inner member, the members being continuously welded together at their abutting lines of juncture and to the periphery of said drum at the inner edge of said inner flange and to the periphery of said drum at its annular end edge surface.

20 6. A reel structure comprising a drum and annular heads fixed to the drum, each head comprising solely an annular sheet having the area thereof adjacent the periphery bent in an arc, and a second annular sheet spaced from the first-mentioned sheet to provide a single unobstructed space in the head, said second sheet having its inner and outer areas bent in an arc to meet the edges of the first-mentioned sheet, and 25 continuous welds formed at the inner and outer points of juncture of the sheets to join the sheets into a unitary hollow head.
